SEWING MACHINE

George Sauer, Berwyn, Ill., assignor to Union
Special Machine Company, Chicago, Ill., a cor-
poration of Illinois

Application September 26, 1946, Serial No. 699,566

7 Claims. (Cl. 112—256)

1

The present invention relates to sewing machines and more particularly, to a lubrication system especially adapted to those sewing machines having a rotary hook. In such machines the provision of means for lubricating the inter-engaging parts of the rotary hook and the stationary bobbin assembly has presented a rather difficult problem. It will be recognized that the provision of any excessive quantity of oil may result in staining of the thread or the throwing of oil on other parts of the machine or possibly upon the work. However, it is essential that an adequate and unfailing supply of oil be maintained for the lubrication of the bearing surfaces between the rotary hook and the bobbin assembly. These bearing surfaces comprise, in the machine to be disclosed herein, a rib formed on one of the parts of the stationary bobbin assembly and a corresponding annular groove or race-way in the hook body. The hook body substantially surrounds the bobbin assembly and supports the latter through the bearing surfaces just described. The bobbin assembly may include a bobbin case and a bobbin case holder and will be referred to herein as a bobbin casing. The bobbin casing is ordinarily held against rotation by providing a suitable connection between the bobbin case holder and the frame or base of the sewing machine. Since the speed of rotation of the rotary hook frequently reaches 10,000 R. P. M., it is apparent that the lubrication of this rather extensive and difficultly accessible bearing surface must be carefully provided for.

It is an object of the present invention to provide a lubricating system for the rotary hook of a sewing machine in which a constant, accurately metered supply of oil is positively conducted to a passageway formed in the hook shaft from which it may be conducted by centrifugal force to the bearing surface between the rotary hook and stationary bobbin casing.

It is a further object of the present invention to provide a lubricating system for the rotary hook of a sewing machine which is unusually reliable in operation, which may be simply and thoroughly cleaned and which includes provision for simple and accurate adjustment in the quantity of oil supplied.

It is a further object of the present invention to provide a lubricating system for the rotary hook of a sewing machine in which the pumping device for supplying oil under pressure is driven by a shaft rotating at a decidedly slower speed than that of the hook shaft whereby the pressure and the quantity of oil supplied by such

2

pumping means may not be excessive and may be simply and easily adjusted. Other and further objects will in part be apparent and will in part become apparent upon a consideration of the following description of a preferred but not necessarily the only form of the invention taken in connection with the drawings accompanying and forming a part of the present specification.

In the drawings:

10 Fig. 1 is a vertical sectional view of a sewing machine in which the present invention may be embodied;

Fig. 2 is a horizontal sectional view taken along the line 2—2 in Fig. 1;

15 Fig. 3 is a detailed sectional view of the hook shaft, hook and bobbin casing in the machine shown in Fig. 1;

Fig. 4 is a vertical section taken along the line 4—4 of Fig. 2; and

20 Fig. 5 is a detailed sectional view of the pumping mechanism in the machine shown in Fig. 1.

Referring now to the drawings and particularly to Fig. 1, there is shown a lockstitch sewing machine of a type to which the present invention is particularly adapted. The machine comprises a base generally indicated at 10 which may comprise a hollow casting the upper surface 12 of which serves as the cloth plate of the machine. The lower portion of the casting is closed as by a plate 14 and an oil-sealing gasket 16. The machine is provided with a hollow standard 18 which communicates with certain of the hollow portions of the base and which may have integrally formed therewith an overhanging arm 20 terminating in a head 22.

25 A main drive shaft 24 extends through the arm 20 and has fixed at its right-hand end, as viewed in Fig. 1, a combined hand-wheel and pulley 26 by which the machine may be operated manually or by power. The shaft 24 extends into the head 22 and is connected with suitable mechanism therein for vertical reciprocation of a needle bar 28 fitted at its lower end with a needle 30.

30 In the upper portion of the standard 18, as shown in Fig. 1, the shaft 24 has fixed thereto a gear 32 meshing with an idler gear 34 which in turn meshes with a gear 36 fixed to a shaft 38 extending generally longitudinally of the hollow base of the machine. Referring now to Fig. 2, it will be observed that the shaft 38 is mounted for rotation in a suitable bearing 40 carried by a web portion 42 of the base casting. At its left-hand end the shaft 38 is rotatably mounted in a bearing 44 carried by the left wall 46 of the base casting. The shaft 38 has formed therein ad-

jacent the wall 46 an eccentric or crank (not shown) with which cooperates an eccentric strap 48 forming a part of a telescopic pitman 50 having a hub 52 freely rotatable upon a suitable pivot (not shown) carried by a feed-rocker 54. The feed-rocker 54 also pivotally carries a hub 56 to which is connected a feed bar 58. Rotation of the shaft 38 is effective through the telescopic pitman 50 and a motion-modifying mechanism 60 attached thereto to rock the feed-rocker 54 and thus to impart horizontal motion to the feed-dog (not shown) carried by the feed bar 58.

The motion-modifying mechanism 60 has not been described in detail herein inasmuch as it is shown and described in full detail in U. S. Patent No. 2,035,508 granted March 31, 1936 to Sauer et al. It should be pointed out that the motion-modifying mechanism 60 is so designed as to impart horizontal movements to the feed-dog of adjustable extent whereby to vary the length of stitches produced by the machine.

Vertical movement is imparted to the feed bar 58 and through it to the feed-dog by means of a crank 62 formed upon the left-hand end of the shaft 38. The specific mechanism for connecting the crank 62 with the feed bar will not be described in detail herein inasmuch as a full description thereof is made in said U. S. Patent No. 2,035,508. The horizontal and vertical motions thus imparted to the feed-dog are such as to produce the four-motion feed normally employed in connection with a feed-dog in a sewing machine of this general type.

The shaft 38 has fixed thereto a gear 64 which meshes with a gear 66 fixed to a rotary hook shaft 68. In view of the nature of the stitch formed by a machine of this type, it is necessary for the hook shaft to make two complete revolutions during the formation of a single stitch. The gear 64 is thus provided with twice the number of teeth provided on the gear 66. It is not at all unusual in the operation of a machine of the type disclosed herein for the machine to form approximately 5,000 stitches per minute and accordingly, the rotary hook shaft must rotate at approximately 10,000 R. P. M.

The right-hand end of the hook shaft, as viewed in Fig. 2, is mounted for rotation in a suitable bushing 70 carried by a web portion 72 of the base casting. An elongated bushing 74 is carried in a lug portion 76 of the base casting as well as in the left wall 46 thereof. The bushing 74 extends from the gear 66 through the casting portions aforesaid and substantially into contact with a thrust collar 78 secured to the hook shaft. The bushing 74, together with the gear 66 and thrust collar 78 thus serves to prevent enwise motion of the hook shaft 68. At its left-hand end the hook shaft 68 has formed thereon an enlarged head 80 upon which the rotary hook (not shown in Fig. 2) is mounted.

Referring now to Fig. 3, the rotary hook is generally indicated at 82 and is shown in position upon the head 80 of the hook shaft 68. The rotary hook 82 has a recess 84 formed therein within which is received a bobbin casing 86. The bobbin casing 86 is provided with a projecting portion 88 which is engaged with a suitable device fixed to the frame of the machine whereby the bobbin casing 86 is held against rotation with the rotary hook 82. It will be understood that the engagement between the projecting portion 88 and the device which holds the bobbin casing 86 against rotation allows for a small

amount of play thereby providing for slight movement of the bobbin casing relative to the machine frame in order that the needle thread loop may be carried around the bobbin casing and be withdrawn through the space provided by the play. This particular construction is old and well-known and has not been illustrated in complete detail herein. The bobbin casing is provided with a rib 90 which is received in an annular groove 92 formed in the recessed portion 84 of the rotary hook 82. In general, the annular groove 92 is formed in the body of the hook 82 as shown at the upper portion of Fig. 3. However, it will be observed that at the lower portion of Fig. 3 two walls of the groove 92 are formed in the hook body while the third wall is defined by an inwardly turned flange 94 formed on a detachable part 96 of the hook mechanism which part is secured to the hook body as by screws 98.

It will be apparent that since the bobbin casing 86 is held substantially against rotation and the hook body 82 is driven for rotation at an extremely high speed, the rib 90 and groove 92 comprise interengaging bearing parts which must be carefully lubricated. It is also apparent that to avoid contact of oil with the thread an excessive quantity of oil cannot be used for lubrication of such bearing. It is known to form the rotary hook shaft with a longitudinal bore therein through which oil may be conducted to the hook body. It is also known to form suitable passageways within the hook body through which oil discharged by the bore in the hook shaft may be thrown by centrifugal force into contact with the bearing surfaces of the interengaging hook and bobbin parts. The present invention is directed to a new and improved structure for the positive supply of oil to the hook shaft bore.

To this end there is mounted in the web portion 72 of the casting, as seen in Fig. 2, a bushing 100 through which the shaft 38 extends. The bushing 100 extends to the right, as viewed in Fig. 2, beyond the web portion 72 and has formed on the exterior surface thereof threads 102 for receiving an internally threaded packing gland 104 within which is positioned suitable packing material 106.

As shown in Fig. 5, an opening 108 is formed in the web portion 72 and extends inwardly thereof into communication with vertically disposed aligned openings 110 and 112 in the web portion 72 and the bushing 100 respectively. The opening 112 communicates with an annular recess 114 formed in the bushing 100 and extending around the shaft 38. A second annular recess 116 is formed in the bushing 100 in horizontal spaced relationship with the annular recess 114. The portion of the shaft 38 extending between the recesses 114 and 116 has formed therein a continuous spiral groove 118. The spiral groove 118 is inclined in such direction that upon rotation of the shaft 38 in its normal direction in operation of the machine, the spiral groove 118 will carry oil from the recess 114 to the recess 116. In the machine shown in the drawings the spiral groove 118 is cut as a right-hand thread would be cut and the shaft 38 normally revolves in a counterclockwise direction as viewed from the left-hand end of Fig. 5.

Referring next to Fig. 2, the annular recess 116 communicates with a horizontally disposed passageway 120 formed in the bushing 100 which in turn communicates with a horizontally disposed passageway 122 formed in the web portion 72.

The passageway 122 includes an enlarged portion within which is positioned a hardened needle valve seat 124 the outer end of which opens into a recess 127 in the web portion 72. A needle 126 is projected through a suitable opening in the base casting and web portion 72 into operative relationship with the needle valve seat 124. The outer end of the needle 126 is threaded as at 128 into the base casting and is supplied with a suitably indexed operating knob 130 and a lock nut 132. Rotation of the adjusting knob 130 is effective to vary the relationship of the needle 126 and the needle valve seat 124 and the needle may be locked in adjusted position by tightening the lock nut 132 against the frame of the machine.

The recess 127 comprises a continuation of the bore in web portion 72 which receives bushing 70 and is closed at its right-hand end as viewed in Fig. 2 by a suitable threaded plug 134.

The hook shaft 68 is provided with a central bore 136 extending throughout the length thereof. The left-hand end of the bore 136 terminates in the head 88 and preferably is flared outwardly as indicated at 138. As shown in Fig. 3, the flared opening 138 communicates with a pocket or recess 140 in the body of the rotary hook 82. As a matter of convenience, the recess 140 may comprise merely an extension of the opening which receives the head 88 of the hook shaft. The recess 140 thus provided may be closed by a disc 142 seated in a recess 144 in the hook body in such manner that the outer surface of the disc 142 is flush with the surface of the recess 84 within which the bobbin casing is carried. It has been found to be particularly desirable in connection with the present invention to provide the disc 142 with a central opening 146 aligned with the bore 136 of the hook shaft. The opening 146 serves as an air vent to prevent the system from becoming air-bound. There is no danger of oil escaping through the vent 146 in view of the fact that the hook body rotates at a very high speed and the quantity of oil normally supplied is sufficient only to form a moving film of oil held by centrifugal force against the inner cylindrical surface of the annular recess 140.

The body of the hook 82 has formed therein a radially-disposed passageway 148 the outer end of which is closed by a plug 150. The passageway 148 communicates with a generally horizontally-disposed passageway 152 extending into the annular recess 92 within which the rib 90 of the bobbin casing is carried. Obviously, a plurality of radial passageways 148 may be provided, if so desired. There is thus defined a continuous oil passageway extending from the spiral pump mechanism on the shaft 38 to the inter-engaging surface 90, 92 of the bobbin casing and rotary hook, respectively.

As shown in Fig. 1, two oil sumps are provided in the lower portion of the base of the machine. The main oil sump is indicated at 154 and extends from the rear wall 45 of the machine to the front wall 46 thereof. Referring briefly to Fig. 2, the main sump 154 will be observed to extend transversely of the machine throughout its entire width. A sight gauge 156 having markings 155 and 157 is shown in Figs. 2 and 4. The gauge 156 extends into the main oil sump for the purpose of visually indicating the level of oil therein. Preferably the gauge 156 is made of a transparent material as disclosed in U. S. Patent

No. 2,301,460 granted November 10, 1942 to Sauer. A hook shaft oil sump 158 is defined between the web portions 42 and 72 and suitable web portions 160 and 162 as seen in Fig. 4. The sump 158 is closed at the bottom by means of a cover plate 164 and gasket 166. A sight gauge 156 similar to the gauge 156 extends into the oil sump 158 and is provided with markings 170 and 172 indicating respectively the upper and lower limits between which the level of oil should be maintained. As shown in Fig. 4 and in Fig. 1, the level of oil in the hook shaft sump 158 will ordinarily substantially submerge the portion of the shaft 38 extending through the sump 158. Thus the level of oil is well above the opening 108 as will be apparent in Figs. 4 and 5. The static head on the body of oil in the sump 158 will therefore insure that oil will flow through the passageway 108 and rise well into the annular recess 114 communicating therewith. Rotation of the shaft 38 and the action of the spiral groove 118 will be effective to draw oil from the annular recess 114 and discharge it into the annular recess 116. The packing gland 184 is provided for the purpose of preventing the escape of oil along the shaft 38.

Oil in the annular recess 116 will be discharged through the passageway 120 (in Fig. 2) and past the needle valve 124, 126. The quantity of oil passing the needle valve and the pressure developed will be dependent upon the adjustment of the needle valve. The oil passing the needle valve 124, 126 will enter the recess 127 and from this recess will flow into the bore 136 of the rotary hook shaft.

In view of the speed of rotation of the hook shaft oil supplied to the bore 136 by the pumping mechanism just described will be distributed as a continuous film over the entire surface of the bore. The film of oil will achieve an average thickness depending upon the rate at which oil is supplied from the spiral pump. As oil is supplied at the right-hand end of the bore, a corresponding amount will be caused to leave the left-hand end of the bore and to enter the hook body 82. It will be appreciated, therefore, that the rate at which oil is supplied to the hook body may be very accurately controlled by manipulation of the needle valve 124, 126. When the machine is stopped, there will be substantially no tendency for oil to continue flowing into the hook body 82. This is a particularly important feature of the invention inasmuch as many previous mechanisms involving gravity or wick feeds for the lubrication of the rotary hook have had the tendency to continue the flow of oil after the machine is stopped. Such continued flow will place excess oil in the hook body where it is likely to be thrown upon the work immediately that the machine is re-started. At the same time a small amount of oil remains distributed throughout the length of the shaft, in accordance with this invention, and such oil is instantaneously available for delivery to the hook raceway as soon as the machine is re-started. Such delivery is brought about through the centrifugal pumping action produced by the sloping surface 138 and the radial duct 148.

The arrangement of the spiral pump on the drive shaft 38 and the provision of direct passageways from the pump to the inner end of the hook shaft offers the distinct advantage that the pump is driven at a speed of rotation only one-half that of the hook shaft. Since a very small quantity of oil is required, it is decidedly advan-

tageous to make use of a relatively low-speed pump capable of moving an adequate quantity of oil under a relatively low pressure. With such an arrangement the adjustment of the needle valve 124, 126 is not unduly critical. When it is desired to flush the hook, it is necessary only to open the needle valve rather widely for a brief period and then to readjust it to normal position as indicated by the indexed knob 130. The excess oil will soon be thrown from the hook and normal operation may be resumed.

From the above detailed description it will be apparent that I have provided a mechanism which accomplishes the objects of the invention.

While an illustrative form of the invention has been disclosed in considerable detail, it will be understood that various changes may be made in the construction and arrangement of the several parts without departing from the general principles and scope of the invention as defined in the appended claims.

I claim:

1. In a sewing machine, the combination of a frame, a rotary hook, a rotary hook shaft, a rotary drive shaft, means connecting said drive shaft with said hook shaft for rotation of said hook, a stationary bobbin casing supported in said hook, said hook and casing having cooperating bearing surfaces requiring lubrication, means within said hook for directing lubricant from a point adjacent the axis of said rotary hook shaft to said bearing surfaces, said rotary hook shaft having a passageway extending axially thereof, means in said frame having a recess therein communicating with the end of said passageway remote from said hook, a rotary pump on said drive shaft, a lubricant reservoir communicating with the intake of said pump, means for directing lubricant from the discharge side of said rotary pump to said recess, an adjustable needle valve interposed between said pump and said recess, and means for indicating the position of adjustment of said needle valve.

2. In a sewing machine, the combination of a frame, a rotary hook, a rotary hook shaft, a rotary drive shaft, means connecting said drive shaft with said hook shaft for rotation of said hook, a stationary bobbin casing supported in said hook, said hook and casing having cooperating bearing surfaces requiring lubrication, means within said hook for directing lubricant from a point adjacent the axis of said rotary hook shaft to said bearing surfaces, said rotary hook shaft having a passageway extending axially thereof, means in said frame having a recess therein communicating with the end of said passageway remote from said hook, a rotary pump on said drive shaft, a lubricant reservoir communicating with the intake of said pump, means for directing lubricant from the discharge side of said rotary pump to said recess, an adjustable needle valve interposed between said pump and said recess, and a knob exterior of said frame for adjustment of said needle valve, said knob having index marks thereon for indicating the position of adjustment of said needle valve.

3. In a sewing machine, the combination of a horizontal-axis rotary hook, a horizontal-axis rotary hook shaft, a horizontal-axis drive shaft, means connecting said drive shaft with said hook shaft for rotation of the latter, a stationary bobbin casing supported in said hook, said hook and casing having cooperating bearing surfaces requiring lubrication, means within said rotary

hook for directing lubricant from a point adjacent the axis of said rotary hook shaft to said bearing surfaces, a passageway extending axially of said rotary hook shaft, and means for supplying lubricant to said passageway, said last-named means comprising a spiral pump carried by said drive shaft, a reservoir for containing a supply of lubricant exclusively for said bearing surfaces, a passageway connecting said reservoir with the intake side of said spiral pump, a discharge passageway from the discharge side of said pump, and an adjustable needle valve associated with said discharge passageway for regulating the quantity of lubricant discharged by said pump into the passageway in said rotary hook shaft.

4. In a sewing machine, the combination of a rotary hook, a rotary hook shaft, a drive shaft alongside said hook shaft, means connecting said drive shaft with said hook shaft for rotation of the latter, a stationary bobbin casing supported in said hook, said hook and casing having cooperating bearing surfaces requiring lubrication, means within said rotary hook for directing lubricant from a point adjacent the axis of said rotary hook to said bearing surfaces, a passageway extending axially of said rotary hook shaft, and means for supplying lubricant to said passageway, said last-named means comprising a spiral groove formed in a portion of said drive shaft closely adjacent to said hook shaft, a bushing surrounding said drive shaft in the region of said spiral groove, said bushing having an annular recess therein communicating with a supply of oil and said recess being positioned at one end of said spiral groove, a second annular recess formed in said bushing adjacent the opposite end of said spiral groove, means for rotating said drive shaft in a direction such that said spiral groove will conduct oil from said first-named recess to said second-named recess, a discharge passageway communicating with said second-named recess, an adjustable needle valve associated with said discharge passageway for controlling the amount of lubricant emerging from said discharge passageway, and means for directing the lubricant thus discharged into the passageway formed in said rotary hook shaft.

5. In a sewing machine, the combination of a rotary hook, a horizontal-axis rotary hook shaft, a horizontal-axis drive shaft alongside said hook shaft, means connecting said drive shaft with said hook shaft for rotation of the latter at a substantially greater speed than that of said drive shaft, a stationary bobbin casing supported in said hook, said hook and casing having cooperating bearing surfaces requiring lubrication, means within said rotary hook for directing lubricant from a point adjacent the axis of said rotary hook to said bearing surfaces, a passageway extending axially of said rotary hook shaft, and means for supplying lubricant to said passageway, said last-named means comprising a spiral groove formed in a portion of said drive shaft closely adjacent said hook shaft, a bushing surrounding said drive shaft in the region of said spiral groove, said bushing having an annular recess therein communicating with a supply of oil and said recess being positioned at one end of said spiral groove, a second annular recess formed in said bushing adjacent the opposite end of said spiral groove, means for rotating said drive shaft in a direction such that said spiral groove will conduct oil from said first-named recess to said second-named recess, a discharge passageway

way communicating with said second-named recess, an adjustable needle valve associated with said discharge passageway for controlling the amount of lubricant emerging from said discharge passageway, and means for directing the lubricant thus discharged into the passageway formed in said rotary hook shaft.

6. In a sewing machine, the combination of a rotary hook, a rotary hook shaft having a passageway extending axially thereof, a drive shaft alongside said rotary hook shaft, means for rotating said drive shaft, means connecting said drive shaft with said rotary hook for rotation of said rotary hook shaft at a higher speed than that of said drive shaft, a spiral pump on a portion of said drive shaft closely adjacent to said rotary hook shaft, means including a passageway having an adjustable needle valve therein for conducting lubricant from said pump to the axial passageway in said rotary hook shaft, a stationary bobbin casing supported by said hook, said hook and casing having cooperating bearing surfaces requiring lubrication, said rotary hook having a recess communicating with the passageway in said rotary hook shaft, and means in said rotary hook for directing lubricant from said recess to said bearing surfaces.

7. In a sewing machine the combination of a frame, a rotary hook, a rotary hook shaft having a longitudinal passageway extending along the axis thereof, a drive shaft alongside said rotary hook shaft, a frame member interposed between said rotary hook shaft and said drive shaft, a reservoir for containing lubricant exclusively for said hook, said reservoir having generally vertical sidewalls and a bottom, one of said sidewalls comprising said frame member, said drive shaft

extending through said reservoir, a spiral pump on said drive shaft, means defining a recess at the intake end of said spiral pump and a passageway connecting said recess with said reservoir, 5 means defining a second recess at the discharge end of said spiral pump, means defining a third recess at the end of said rotary hook shaft opposite said hook, said second recess and said third recess being located on opposite sides of 10 said frame member and being substantially opposed to one another, said frame member having a passageway extending therethrough and connecting said second recess and said third recess, and an adjustable needle valve located in said 15 last-named passageway to restrict the area thereof to adjustable extents whereby to permit the flow of varying quantities of lubricant under pressure from said spiral pump to said longitudinal passageway in said rotary hook shaft.

GEORGE SAUER.
